(57) **CLAIM**

The ornamental design for a leak-proof baking mat, as shown and described.

DESCRIPTION

FIG. 1 is a top perspective view of a leak-proof baking mat, showing a first embodiment of our new design;

FIG. 2 is a top plan view thereof;

FIG. 3 is a front elevation view thereof;

FIG. 4 is a rear elevation view thereof;

FIG. 5 is a right-side elevation view thereof;

FIG. 6 is a left side elevation view thereof;

FIG. 7 is a bottom view thereof;

FIG. 8 is a top perspective view shown in an environment of use thereof;

FIG. 9 is a top plan view of a leak-proof baking mat showing a second embodiment of our new design;

FIG. 10 is a front elevation view thereof;

FIG. 11 is a rear elevation view thereof;

FIG. 12 is a right-side elevation view thereof;

FIG. 13 is a left side elevation view thereof;

FIG. 14 is a bottom view thereof; and,

FIG. 15 is a top perspective view shown in an environment of use.

The broken lines in the figures depict environmental subject matter and form no part of the claimed design.

1 Claim, 9 Drawing Sheets
